UNITED STATES PATENT OFFICE.

WILLIAM E. SMITH, OF PINEVILLE, KENTUCKY.

SAFETY-ENVELOP.

No. 905,757.

Specification of Letters Patent.

Patented Dec. 1, 1908.

Application filed November 19, 1907. Serial No. 402,889.

To all whom it may concern:

Be it known that I, WILLIAM E. SMITH, a citizen of the United States, residing at Pineville, in the county of Bell and State of Kentucky, have invented new and useful Improvements in Safety-Envelops, of which the following is a specification.

This invention relates to improvements in envelops, of that class in which money or 10 valuables are transmitted through the mail, and the object of the invention is to provide an envelop of this character whereby opening of the envelop by unauthorized persons will become difficult, and such an opening 15 readily detected.

To these and other ends the invention resides in the formation of safety envelops comprising substantially a series of compartments folded upon each other and effectively 20 sealed as will hereinafter be fully described and claimed.

In the drawings, Figure 1 is a view of an envelop embodying my improvement, and showing the same in an open position. Figs. 25 2, 3, 4, 5, 6 and 7 illustrate the various figures employed in the sealing of my envelop, and Fig. 8 illustrates the envelop closed.

The present invention is primarily intended as an improvement upon the envelops 30 now in general use for transmitting registered letters or packages through the mail. The construction in general use comprises an envelop of the ordinary formation having a sealing flap provided with adhesive sub- 35 stance and a series of small flaps formed upon the face of the envelop, provided with adhesive substance and adapted to be secured upon the sealing flap. With this construction the sealing flap is effectively retained upon the envelop, but in the transmission 40 of the envelop through the mail the corners of the envelop become worn so that it is comparatively easy to insert a knife or other sharp instrument between the worn 45 edges of the envelop and extract the contents without much danger of detection. It has been known that in the course of long journeys by the envelop now employed in the transmission of registered mail matter, the 50 edges of the envelop, due to the constant handling by various authorities through whose hands it passes, and whose indorsement is required upon the envelop, have become so worn as to separate and the contents become lost in transit. It will thus be seen that the present construction of en-

velops designed for the transmission of registered matter is defective for the reasons above enumerated, it being comprised of a single compartment, the edges easily become 60 worn in transit and the contents easily accessible to unscrupulous persons, and with little fear of detection as the loss of the contents can easily be laid upon the wearing of the edges of the envelop in the course of 65 handling and transit.

To overcome the deficiencies of the envelop now used in the transmission of registered mail matter, I have provided a safety envelop comprising a compartment and a 70 series of protecting flaps folded upon each other, and over the compartment, the flaps being effectively sealed in a novel manner whereby the removal of the sealing flap of the envelop from the body of the envelop is 75 entirely prevented without detection and whereby the edges of the envelop liable to wear in the course of transit of the envelop will not permit of the removal of the contents of the envelop. 80

To accomplish the purposes of the invention, I have provided the novel construction of envelops illustrated in the accompanying drawings, in which the numeral 1 designates a blank sheet of heavy paper comprising 85 a series of faces 1, 2, 3 and 4, a sealing flap 5 and a series of side flaps. The face 1 has its side flaps 6 provided with a slit 7 adjacent the line of folding 8, and a pair of slits or openings 10 near its free end and at 90 the lower corner thereof. The face 2 is provided with side flaps 11 upon each of its sides, and the face 3 is likewise provided upon its sides with the side flaps 12. The sealing flap 5 is of a width approximately 95 equaling that of the face 1, from which it is extended and comprises a body portion 13 having a slit 14 and being provided with extending V-shaped fingers 15 upon its ends, and with the central tongue 16 having the 100 ears 17, and terminating in a lip 18. The slot 14 within the body portion 13 of the sealing flap 5 is of a width equaling that of the tongue 16. The V-shaped fingers 15, the ears 17 and the lip 18 are each adapted to 105 receive a coating of adhesive material designated by the numeral 19.

In assembling my improved envelop the contents are first placed upon the face 3 of the envelop and the end flap 4 folded upon 110 the line 20 upon the face 3, the side flaps 12 are then folded upon the lines 21 over the

end face 4. The compartment thus formed is now folded upon the line 22 over the face 2 and the side flaps 11 are each folded upon the lines 23 towards each other and over 5 the compartment. The face 2 together with the folded portions of the device are now folded upon the line 24 and the side flaps 6 folded thereon and over each other upon the lines 8. When the side flaps 6 are folded 10 the slits or openings 10 of the flaps upon each side of the face 1 of the envelop register with each other and are in a direct line with the tongue 16 and the slit 14 of the sealing flap 5. The slits 10 of the side flaps 6 and 15 the slit 14 of the body portion of the sealing flap 5 are of a width equaling each other and the width of the tongue 16.

When the side flaps 6 are in their folded position the sealing flap 5 is bent forward 20 upon the line 25 and the V-shaped fingers inserted within the slits 7 of the side flaps 6, the adhesive substance 19 upon the fingers being moistened to insure the adhesion of the fingers to the flaps. The ears 17 of the 25 tongue 16 are now folded upon themselves on the lines 26, and the tongue inserted through the nearest slot 10 within the side flaps 6 and brought forward between the flaps and the outer side of the face 2 as 30 clearly illustrated in Fig. 4 of the drawings. The tongue 16 is now bent rearwardly and the lip 18 inserted within the outer opening or slit 10 of the side flaps 6 and brought forward upon the tongue 16 through the opposite slits 10 of the flaps 6 as clearly illustrated in Fig. 6 of the drawings. The ears 17 are now bent rearwardly to their normal flat position, the adhesive material 19 moistened, the tongue 18 having its adhesive material moistened, is now inserted within the 40 slit 14 of the sealing flap 5, as clearly illustrated in Fig. 7 of the drawings, and the ears 17 pressed downwardly to insure the adhesion of the ears to the envelop, and the 45 envelop is completed and presents an appearance as illustrated in Fig. 8 of the drawings.

From the above description it will be noted that I have provided an envelop 50 adapted for containing registered mail matter which is provided with a compartment adapted for containing the mail matter which is protected upon all of its sides and edges by a series of flaps and faces which will effectively prevent accidental losing of 55 the contents of the envelop while in transit, due to the wearing of the edges of the envelop and which, should the edges of the envelop become separated will warn the authorities that such separation was fraudulently made. It will be also observed that I have provided a novel means of sealing the envelop so as to entirely prevent its fraudulent opening by steaming or like means of opening envelops to which the present form 60 of envelops is susceptible.

While I have described the preferred form of construction of envelops as the device now presents itself to me, it will be understood that minor details of construction within 70 the scope of my invention may be resorted to without departing from the spirit or sacrificing any of the advantages of the invention.

Having thus fully described the invention 75 what is claimed as new is:

In a safety envelop an elongated body having longitudinal scores, a series of side flaps projecting laterally from the body between the scores, said flaps diminishing in 80 length from the top to the bottom flap, the top flaps having a series of slits, and a sealing flap having a slit and being provided with projecting fingers and a reduced central tongue, and side ears upon the tongue 85 substantially as and for the purpose set forth.

In testimony whereof I affix my signature in presence of two witnesses.

WILLIAM E. SMITH.
